Carpets

DESIGN.

—o—
H. NORTH.

CARPET.

No. 17,214.

Patented Mar. 29, 1887.

UNITED STATES PATENT OFFICE.

HOWARD NORTH, OF YONKERS, NEW YORK, ASSIGNOR TO JOHN BROMLEY
& SONS, OF PHILADELPHIA, PENNSYLVANIA.

DESIGN FOR A CARPET.

SPECIFICATION forming part of Design No. 17,214, dated March 29, 1887.

Application filed February 25, 1887. Serial No. 228,891. Term of patent 3½ years.

To all whom it may concern:

Be it known that I, HOWARD NORTH, a subject of the Queen of Great Britain, residing at Yonkers, in the county of Westchester and State of New York, have invented and produced a new and Original Design for Carpets; and I do hereby declare that the photographic print accompanying this specification conveys to any one skilled in the art a clear understanding of the same, and is sufficient to enable such person to use my invention.

The leading features of my design consist in a series of diamond and triangle shaped ornamental figures, as shown at A, B, C, D, and E. At F and other parts of the design the figures are formed or outlined by straight lines and lines at sharp right angle. The above-described forms, as shown in the print, are known in "Grammar of Ornamentation" as that of "Savage Tribes."

At G is represented a figure known as a

"Greek ornament." This ornament is placed on each side of the large diamonds and triangles, as shown, near the center of the print.

In other parts of the design are shown cubes. 25 These cubes are formed by joining four triangles, as shown at H.

What I claim as my invention is—

The design for a carpet, consisting of a series of diamond and triangle shaped figures, 30 with a series of block figures formed by straight lines and lines at sharp right angles, and showing ornamental Greek figures on each side of the large diamonds and triangles, and showing a series of cubes formed by joining four triangles, the whole as shown in the photographic print. 35

HOWARD NORTH.
